CLAIM

The ornamental design for a change module, as shown and described.

DESCRIPTION

This application contains subject matter related to the following co-pending U.S. design patent application:
Application Ser. No. 29/551,365, filed Jan. 13, 2016 and entitled "Change Module."

FIG. 1 is a top perspective view of a first embodiment of a change module according to the design;

FIG. 2 is bottom perspective view thereof;

FIG. 3 is a side view thereof;

FIG. 4 is an additional side view thereof;

FIG. 5 is a top view thereof;

FIG. 6 is a bottom view thereof.

FIG. 7 is a top perspective view of a second embodiment of the change module according to the design;

FIG. 8 is bottom perspective view thereof;

FIG. 9 is a side view thereof;

FIG. 10 is an additional side view thereof;

FIG. 11 is a top view thereof; and,

FIG. 12 is a bottom view thereof.
